(57) **CLAIM**

The ornamental design for a tread band portion of a tire for bicycles, as shown and described.

DESCRIPTION

FIG. 1 is a front, right perspective view of a tread band portion of a tire for bicycles, showing our new design; FIG. 2 is a top plan view thereof; FIG. 3 is a bottom plan view thereof; FIG. 4 is a front elevation view thereof; FIG. 5 is a back elevation view thereof; FIG. 6 is a left side view thereof; and, FIG. 7 is a right side view thereof.

The portions of the tire depicted in long broken dashed lines of even length form no part of the claimed design.
